UNITED STATES PATENT OFFICE.

AUSTIN F. JACKSON, OF TAUNTON, MASSACHUSETTS, ASSIGNOR TO THE REED & BARTON CORPORATION, OF SAME PLACE.

DESIGN FOR A HANDLE FOR SPOONS, &c.

SPECIFICATION forming part of Design No. 22,066, dated December 20, 1892.

Application filed November 22, 1892. Serial No. 452,884. Term of patent 7 years.

To all whom it may concern:

Be it known that I, AUSTIN F. JACKSON, a citizen of the United States, residing at Taunton, in the county of Bristol and State of Massachusetts, have invented and produced a new and original Design for Handles of Spoons and other Similar Articles, of which the following is a specification, reference being had to the accompanying drawing, forming a part

thereof.

The figure is an upper or front face view of a spoon handle embodying my design.

The leading feature of my design is a special arrangement of the leaves, blossoms, and buds of the myrtle shrub as follows. Around the shank of the spoon handle is entwined a part of the vine with two leaves *a* wrapped well down upon the shank and other leaves *a'*

spreading out divergently toward the end of the handle. Near the end of the handle is a *b* full blown myrtle blossom. At its inner edge on the left hand side is a bud *c*, and at the outer end and protruding in the middle line of the handle are two projecting buds *d*. The outer edges of the leaves, blossoms, and buds impart their irregular outline to the margin of the handle.

What I claim is,

The design for the handles of spoons and other similar articles as herein shown and described.

AUSTIN F. JACKSON.
